UNITED STATES PATENT OFFICE.

CHARLES A. JUENGST, OF CROTON FALLS, NEW YORK.

PAPER-FEEDING MECHANISM.

SPECIFICATION forming part of Letters Patent No. 779,784, dated January 10, 1905.

Original application filed July 18, 1900, Serial No. 24,017. Divided and this application filed January 18, 1902. Serial No. 90,267.

To all whom it may concern:

Be it known that I, CHARLES A. JUENGST, a citizen of the United States, residing at Croton Falls, in the county of Westchester and State 5 of New York, have invented an Improvement in Paper-Feeding Mechanism, of which the following is a specification.

My invention relates to devices for gathering signatures and sheets from superimposed 10 piles and delivering the same upon a conveyer device; and the object of my invention is to provide an adjustability for the gripper-jaws accommodating them to the thickness of signatures or sheets and to provide suitable devices 15 for operating the grippers.

In carrying out my invention I provide pivoted gripper devices with gripper-fingers and devices for moving the same toward and from the superimposed pile of signatures or sheets 20 and also for opening and closing the grippers to engage, remove, and then drop the signatures or sheets; also, devices for adjusting the relation of the gripper-jaws to one another to provide for signatures or sheets of varying thicknesses. 25

In the drawings, Figure 1 represents, by an elevation and partial section, parts of a signature-gathering machine embodying my improvements. Fig. 2 is a plan of so much of 30 the machine shown in Fig. 1 as may be necessary for fully understanding the same, and Fig. 3 is a sectional plan at $\alpha\alpha$ of Fig. 1.

This application is a division of an application for a signature-gathering machine filed 35 July 18, 1900, Serial No. 24,017.

a represents a base-frame of the machine, and a' and a'' bracket-frames, and at the upper ends of the bracket-frames a'' are head-bearings a^3 for a shaft g , hereinafter referred to. 40

b' represents parts of a conveyer device upon which the signatures or sheets b are delivered and by which they are removed. These conveyer devices are in suitable ways provided upon and supported by the base-frame a . This 45 base-frame also carries a shaft c , on one end of which is a crank-disk c' and cam c^2 , adjacent to one another, the crank-disk c' performing the function of swinging the gripper devices and the cam c^2 of opening and closing 50 the grippers.

d represents a bed or plate for a pile of superimposed signatures or sheets d' , e a bar of the bracket-frame a^2 , and e' a stop-plate connected thereto and against which the advancing edges of the signatures or sheets bear. 55

f is a pneumatic sucker device pivotally mounted on a shaft f' , which swings the same.

So far the parts described form no essential portion of my present invention.

The shaft g in the head-bearings a^3 is adapted to oscillate. This movement is effected by a crank-arm 2 and a rod 3, which at one end is pivotally connected to the free end of the crank-arm 2 and at the other end is pivoted to the crank-disk c' . 60

i is a shaft, and i' bracket-arms, in one end of which the shaft i is pivoted, the other ends of said bracket-arms being secured to the shaft g . On one end of the shaft i is a crank-arm r , and a rod r' is at one end pivotally connected to the free end of the crank-arm r and at its other end carries a roller 7, bearing upon the surface or periphery of the cam c^2 . A spring 8, secured at one end to the bracket-frame a' at its free end, enters a notch in the 75 rod r' above the roller 7, performing the function of holding the rod and the roller against the periphery of the cam, but yielding for the performance of the functions of the cam.

Upon the shaft i is a bracket-arm 9, secured at its hub to said shaft. A sleeve 10 is provided with a pin which passes through the hub on the free end of the bracket-arm 9. A rod 11 passes freely through the sleeve 10. Its upper end is threaded, and a head 12 screws 80 on the upper threaded end of said rod, and there is preferably a clamping-nut above this head. A nut 14 screws upon a threaded portion of the rod 11, and between this end 14 and the sleeve 10 there is a helical spring 13 85 around the rod 11. This spring is under tension between the sleeve 10 and the nut 14, so as to hold the head 12 tightly against the upper surface of the sleeve 10. This nut may be moved along the rod 11 to apply more or less 90 tension to the spring 13, and the head 12 may be moved more or less along the rod 11 to change the adjusted relation of the rod 11 to the sleeve 10. The lower end of the rod 11 is threaded and screws into a head 15, there 95 100

being a nut 16 for clamping the position of the parts with reference to one another. An adjustability, if desired, of the rod 11 in its relation to the head 15 may at this latter point 5 be effected; but I prefer that the adjustability be effected at the upper end of the rod 11 by the parts hereinbefore described.

The machine may be provided with one or 10 a series of gripper-arms *k*, secured to the oscillating shaft *g*. The lower end of the gripper-arm *k* is provided with a head *k'*, with a guide 15 17, and with a stationary gripper-finger 18, and at its lower end with a pivot-pin 19. A gripper-arm *l* is secured by the pivot-pin 19 to the head *k'* at the lower end of the gripper-arm *k*, and said arm at its forward end carries a gripper 20 21 and at its other end is connected to the head 15 by a pivot-pin 20.

I have shown in the drawings double radial 25 arms *h h'*, with hub centers through which the shaft *g* passes and to which the arms are secured and with hub ends for bars 4 5, the bar 5 being provided with a groove 6, as shown, and I have also shown a stop-arm *m*, connected 30 by a pivot-pin 22 to the gripper-arm *k*, the free end of which stop-arm *m* is provided with a hook *m'*, and a link *n* at one end pivotally connected to the bracket-arm 9 and at its lower end loosely pivoted to the arm *m*, and there 35 is a detector-rod *o* at its upper end pivoted to the stop-arm *m* and passing through the guide 17 and at its lower end provided with a hook located in openings in the gripper-fingers 18 and 21.

35 The arm *m* and the parts associated therewith move with the gripper-arm *k*, and the hook *m'* of the arm *m* is adapted to engage the groove 6 of the arm 5 when the grippers have failed to engage a signature or sheet 40 and by such engagement to swing the radial double arms *h h'* and effect the stopping of the machine; but these devices, as well as the devices actuated thereby for stopping the machine, form the subject of a separate application, which is also a divisional application of 45 my former application, Serial No. 24,017.

In the position of the parts as shown in Fig. 1 the grippers are open. The gripper-arm *k* and the parts connected therewith are swung 50 forward toward the superimposed pile of signatures or sheets by the crank-arm 2, connecting-rod 3, the disk *c'*, and the shaft *c*. As these devices move toward the signatures or sheets and just at the time that the open 55 grippers pass over the edge of the signature or sheet the gripper-fingers are closed upon the signature or sheet by the crank-arm *r*, the rod *r'*, the cam *c''*, and the shaft *c* moving the shaft *i* and swinging the bracket-arm 9, the rod 11, and gripper-arm *l* and the parts connected therewith independent of the movement of the gripper-arm *k*, so as to close the gripper-fingers and engage the signature or sheet and to remain closed by virtue of the 60 operative surface of the cam *c''* until the grip-

per-arm *l* has been moved in the opposite direction by the shaft *g*, the crank-arm 2, connecting-rod 3, and disk *c'* to almost the position shown by full lines in Fig. 1, when the cam *c''* will again effect the operation of the 70 gripper-arm *l* and the gripper-finger 21 to open the same and discharge the signature or sheet upon the conveyer device *b b'* for the removal thereof.

From the foregoing description it will be 75 apparent that the upper end of the rod 11 passes freely through the sleeve 10 and that when the shaft *i* is turned and the bracket 9 swung the pressure applied by this movement to the sleeve 10 bears upon the spring 13 to 80 compress the spring. Sufficient tension is applied to this spring so that this movement has no compressive action, but at once moves the rod 11 downward and swings the gripper-arm *l* on its pivot-pin 19 to bring the movable 85 gripper-finger toward the fixed gripper-finger, so as to take hold of the signature or sheet. Should the adjusted relation of these parts not be made with sufficient accuracy to bring the gripper-fingers together into just 90 the desired relation and should there be any excess movement of the sleeve 10 with reference to the rod 11, which would tend to apply a considerable pressure to the gripper-fingers, then the spring 13 will yield to take up 95 this excess movement or compressive action, so that no injury can result to the gripper-fingers or to the signature or sheet held thereby.

I claim as my invention—

1. In a paper-feeding mechanism, the combination with an oscillating shaft and a swinging gripper-arm, and means for moving the same, of a fixed gripper-finger carried by the gripper-arm, a gripper-finger pivotally connected to said gripper-arm and coacting with the fixed gripper-finger, and means having an adjustable relation supported by said oscillating shaft and coacting with said movable gripper-finger for adjusting the relation of the gripper-fingers to accommodate different thicknesses of signatures or sheets.

2. In a paper-feeding mechanism, the combination with an oscillating shaft and a swinging gripper-arm and means for moving the same, of a fixed gripper-finger carried by the gripper-arm, a gripper-finger pivotally connected to said gripper-arm and coacting with the fixed gripper-finger, means having an adjustable relation supported by said oscillating shaft and coacting with said movable gripper-finger for adjusting the relation of the gripper-fingers to accommodate different thicknesses of signatures or sheets, and means adapted to yield under excess of pressure applied to the gripper-fingers.

3. In a paper-feeding mechanism, the combination with an oscillating shaft and a swinging gripper-arm and means for moving the same, of a fixed gripper-finger carried by the

gripper-arm, a gripper-finger pivotally connected to said gripper-arm and coacting with the fixed gripper-finger, a rod pivotally connected to a part of the movable gripper-finger, 5 means pivotally connecting the upper end of the rod to the said oscillating shaft, means for adjusting the relation lengthwise of the rod to said latter supporting device, and means also applying tension to said parts and 10 which means are adapted to yield under excess of pressure applied to the gripper-fingers.

6. In a paper-feeding mechanism, the combination with an oscillating shaft, a gripper-arm secured thereto and a fixed gripper-finger 15 at the lower end of said arm, of a movable gripper-finger pivoted to the lower end of said gripper-arm, means for opening and closing said gripper-fingers, a rod having threaded portions, means for pivotally connecting the 20 same to the movable gripper-finger, a shaft connected to the devices for opening and closing the grippers, a bracket-arm connected to said shaft, a sleeve pivotally connected to said bracket-arm and through which the upper 25 end of the aforesaid threaded rod passes, and means connected to the said rod and coacting with the said sleeve for adjusting the position of the said rod and sleeve and for applying tension with the adjustment.

7. In a paper-feeding mechanism, the combination with an oscillating shaft, a gripper-arm secured thereto and a fixed gripper-finger at the lower end of said arm, of a movable gripper-finger pivoted to the lower end 30 of said gripper-arm, means for opening and closing said gripper-fingers, a rod having threaded portions, means for pivotally connecting the same to the movable gripper-finger, a shaft connected to the devices for opening and closing the grippers, a bracket-arm connected to said shaft, a sleeve pivotally connected to said bracket-arm and through which the upper end of the aforesaid threaded rod passes, and means connected to the said rod and coacting with the said sleeve for adjusting the position of the said rod and sleeve and for applying tension with the adjustment.

8. In a paper-feeding mechanism, the combination with a fixed gripper-finger, of a gripper-arm and movable gripper-finger pivotally connected to the support of the fixed gripper-finger, a head 15 pivotally connected to the opposite end of the gripper-arm, a rod 11 at one end secured to the head 15, a bracket-arm 9 and means for swinging the same, a sleeve 10 pivotally connected to the bracket-arm 9 and through which the upper end of the rod 11 passes, the upper end of said rod having screw-threaded portions, a threaded head 12 80 on said rod 11 above the sleeve 10, and a lock-nut above said head, a nut 14 movable longitudinally upon a threaded portion of said rod 11, and a helical spring 13 surrounding said rod between the nut and the under surface of the sleeve 10, substantially as set forth.

Signed at Croton Falls, in the county of Westchester and State of New York, this 22d day of August, A. D. 1901.

CHARLES A. JUENGST.
